ILLUMINATED TOY VEHICLE

Filed Feb. 21, 1949

UNITED STATES PATENT OFFICE

2,599,208

ILLUMINATED TOY VEHICLE

Allan D. Starr, Carlinville, Ill.

Application February 21, 1949, Serial No. 77,572

1 Claim. (Cl. 46—203)

1

The present invention relates to a child's toy and, more particularly, it relates to an electrically illuminated toy of the type which may be pulled along the floor by means of a pull cord.

It is the primary object of the invention to provide a durable and inexpensive toy suitable for children between the ages of one and five years embodying lasting attraction and fascination.

Another object of the invention is to provide a new and improved child's pull toy embodying a novel electric dry-cell lighting circuit as an illuminating source within the toy.

A further object of the invention is to provide a new and improved electrically illuminated child's pull toy which will become illuminated only when the toy is being pulled along a surface by its pull cord.

Other objects of the invention will appear from the following description taken in connection with the drawing, in which:

Fig. 1 is a perspective view of the toy, showing its outward appearance;

Fig. 2 is a longitudinal elevational view partly broken away to show the interior of the toy, particularly the dry-cell lighting unit forming a part of the invention;

Fig. 3 is a front sectional view taken along the plane 3—3 of Fig. 2;

Fig. 4 is a top plan view of the dry-cell lighting unit within the body of the toy;

Fig. 5 is an enlarged side plan view of a portion of the dry-cell lighting unit to more clearly illustrate the spring-switch contacting means for completing the electric circuit;

Fig. 6 is a longitudinal elevational view similar to that of Fig. 5 but showing certain modifications in the construction of the dry cell lighting unit structure; and

Fig. 7 is illustrative of the manner in which the dry-cell lighting unit of Fig. 2 is adaptable to a toy automobile.

With reference to Fig. 1 of the drawing, there is shown a child's pull toy comprising a hollow rectangular body 10 having its forward bottom edge rounded or sledded and having a pull cord 12 extending from a grommeted aperture 14 centrally located in the forward end of the body, said pull cord being secured within the body of the toy as will be hereafter more fully described.

The body of the toy may be constructed of cardboard, plywood, plastic, sheet metal or any other suitable material which is impervious to light. The top, ends and sides of the toy body are provided with the openings of Figures 16, 18 and 20. These openings may take any approved

2

design, such as stars, hearts, crescents, or the outline of airplanes, ships and the like. The possibilities in this respect are unlimited. Vari-colored configurations of openings are attained by lining the openings on the inside of the toy with transparent paper, film or the like of suitable colors as indicated at 21.

The body 10 has a lid 22 hinged to the front end portion 24 such that it may be lifted to provide access to the interior of the body. In its closed position, the hinged top 22 is secured by a snap hook or other suitable fastener 25 between the top and the back end of the body.

Referring now to Figs. 2, 3, 4 and 5 of the drawing, there are shown various views of the novel dry-cell lighting unit embodied by and forming a part of the present invention. The lighting unit comprises essentially a metal base plate 30; forward, intermediate and rearwardly disposed dry-cell holding and contacting means 32, 34 and 36; a forwardly disposed flexible switch or contacting blade 38, an electric light bulb 40 and an electric dry-cell 42. A pull cord 12 is seen as passing through the aperture 14 from the outside of the toy body to the interior thereof, leading around and through an eye 44 and having its end secured to the top of the switch blade 38 at 37.

The base plate 30 is provided with forwardly and rearwardly located tangs 33 as a means for positively securing the base plate to the bottom of the interior of the toy body in the manner illustrated.

The base plate 30 is further provided with centrally located clips 34 and 35 positioned to receive and hold the dry-cell 42 in a fixed position on the base plate 30. While the manner in which the dry-cell is secured to the base plate is merely a matter of detail in construction, Figs. 2, 3 and 4 show a simple and effective structure wherein a rearwardly holding and contacting blade 36 has been stamped out of the sheet metal of the base plate and bent upwards thereto in the manner shown. Likewise, the two forward stub fingers 32, 32 have been stamped out of the sheet metal of the base plate and bent upwardly at right angles thereto to provide forward abutments, the distance between the holding stubs 32, 32 and the rear contacting blade 36 being such as to closely accommodate the dry-cell 42; positive longitudinal holding of the dry-cell against the forward abutment stubs 32, 32 being effected by the spring clip action of the rear contacting blade 36 which is seen to project upwardly from the base plate 30 and in contact with the rear

transverse vertical terminal surface of the dry-cell.

Transverse positioning and anchoring of the dry-cell 42 with respect to the base plate 30 is accomplished by the intermediate metal clips 34 and 35. As shown in the drawing, these clips are arced to conform with the perimeter of the cylindrical dry-cell 42. The left-hand clip 34 is arced upwardly a distance such as to terminate at a point on top of the dry-cell above the longitudinal axis and is provided with a vertically and transversely disposed eye 44 at its upper end.

The left-hand clip 35 likewise extends upwardly from the base plate following the periphery of the dry-cell cylindrical surface but only to a point slightly above the projected longitudinal axis of said dry-cell cylinder, whereby there is an adequate distance between the ends of the right and left-hand clips to permit insertion and removal of the dry-cell.

While I have illustrated and described a preferred means for positioning and holding the dry-cell on the base plate, it should be recognized that a variety of other perhaps equally suitable means may be employed and it is not intended that the present invention be limited to the structure and means illustrated. For instance, other standard sizes and shapes of electric dry-cells may be used which would necessitate modifications in the anchoring structure. In this connection, it is pointed out that all parts of the present invention, particularly the lighting unit structure, have been designed to lend themselves to simplicity and economy in manufacture and it is contemplated that the base plate 30, the tangs 33, 33 and 36, the holding and contacting parts 32, 34, 35 and 36 may be stamped and formed in a single operation from sheet metal material.

With further reference to the drawings, and particularly to Figs. 2, 3, 4 and 5 thereof, one of the features of the present invention is the flexible spring switching blade 38 centrally disposed forward of the dry-cell 42 and extending upwardly from the base plate substantially vertical thereto and having its lateral surface at right angles with the longitudinal axis of the dry-cell. This spring blade has a bottom flange portion 39 which is riveted, welded or otherwise positively attached to the base plate 30. The switch blade 38 is provided with a screw socket 46 intermediate the base plate and its upper end, extending through the blade for receiving the screw shell terminal of a light bulb 40. The bulb 40 is of the standard flash light type. As illustrated, when the bulb 40 is screwed into the socket 46 the center terminal of the bulb will protrude through the back side of the switch blade. The switch blade 38 is further provided at its upper end with a small eye indicated at 37.

To make the toy operative, one end of the pull cord 12 is attached to the upper end of the switch blade 38 at 31 and led back through the transverse eye 44, and then forward through the grommeted aperture 14 in the front end of the toy body to the exterior thereof. The pull cord 12 may be of any suitable length to facilitate the pulling of the toy by a child.

In Fig. 2 the pull cord 12 is shown normally slack, under which condition the switch blade 38 will be normally parallel with the forward face of the dry-cell 42 and spaced therefrom to hold the center terminal of the bulb 40 out of contact with the center positive terminal 48 of the dry-cell.

As illustrated in Fig. 4, when a forward pull is

applied to the external free end of the pull cord, the cord will become taut and the pull transferred through the cord to the switch blade 38 which will be flexed or distorted to bring the center terminal of the bulb 40 into contact with the center terminal of the dry-cell, whereby the light circuit will be completed and the toy body thereafter motivated along a surface in the direction of pull.

As can be understood from the foregoing description of the association of the base plate 30, the rear holding blade 36, the forward switch blade 38, the bulb socket 46 and the bulb 40, constitute a simple lighting circuit for the lighting of the bulb 40 when its center terminal is brought into electrical contact with the center positive terminal of the dry-cell. As will be hereafter more clearly pointed out, it is important to the proper function of the spring switch blade 38 that it be made of spring steel or other conducting metal alloy having sufficient elasticity that the blade will not become permanently distorted but will always return to a normally vertical and out of contact position with respect to the dry-cell when tension on the pull cord 12 is released. Fig. 5 of the drawing clearly illustrates the switch blade structure in its normal and distorted positions. It should be further recognized that the proper function of the lighting unit requires that the spring resistance of the flexible switching blade 38 be slightly less than the frictional resistance of the toy against forward pull along a surface, such that when a pull is applied to the cord 12, the immediate effect will be the actuating of the switch blade to close the lighting circuit, following which the toy will be motivated in the direction of pull.

Fig. 6 of the drawing illustrates a simplified modification in the lighting unit structure wherein the dry cell is transversely held in place on the base plate by an upwardly open metal U-shaped spring clip 50, welded or otherwise mounted on the base plate. At the forward end of the base plate there is a rigid bulb holding bracket 52 having a socket 46 for receiving the light bulb 40 so that the center terminal of the dry cell will abut the rearwardly protruding center terminal of the light bulb to effect electrical contact and to provide a forward abutment for fixed longitudinal positioning of the dry-cell. To the rear of the dry-cell 42 is a spring switch blade 54 welded or otherwise secured to the base plate and projecting upwardly normally parallel to and extending slightly above the rear surface portion of the dry-cell. The upper end of the switch blade is provided with an eye or the like to which one end of the pull cord 12 is attached, said pull cord thereafter leading directly through the aperture 14 to the front exterior of the toy. As shown in Fig. 6, tension applied to the pull cord will distort or flex the switch blade 54 into contact with the rear surface of the dry-cell, thereby completing the electric circuit and causing the light bulb 40 to burn. Releasing the tension on the pull cord, the spring action of the switch blade 54 will cause it to return to its normally parallel and out of contact position with respect to the rear terminal surface of the dry-cell, the circuit will be broken and the light bulb will go out.

The essential difference between the two lighting unit constructions is that in the first described structure, the switch blade is in front of the dry cell and is distorted to bring the bulb 40 into contact with the dry-cell terminal by means of the indirect pull on the pull cord, while in the

simplified modification, shown in Fig. 6, the bulb holding bracket 52 is rigid and the circuit closing means is the switch blade 54 to the rear of the dry-cell and is distorted into contact therewith by a direct pull on the pull cord.

From the standpoint of economy in manufacture, this latter modification is perhaps to be preferred, it being understood, however, that both constructions obtain the same results in substantially the same way.

Fig. 7 of the drawing illustrates the manner in which the lighting unit of Figs. 2, 3 and 4 may be adapted for use in other types of children's pull toys, such as toy automobiles, airplanes, boats, etc., to illuminate such toys and whereby the electric illuminating means will function automatically when the toy is pulled by means of a pull cord. In this instance, the openings in the body of the toy are limited to two circular light emitting apertures 56 in the front of the toy to simulate automobile head lights when the toy is being pulled.

From the foregoing description, it is seen that the present invention is directed toward a new and novel toy particularly suitable for young children between the ages of one and five years, the novelty of which resides in the fact that the invention provides a mechanically simple means whereby inexpensive children's pull toys of the types described are electrically illuminated by a dry-cell light circuit and wherein such lighting is entirely and automatically controlled by the child and made operative when the toy is being pulled along the floor or other surface and wherein the lighting circuit will be automatically rendered non-operative when the toy is not being pulled, thereby assuring maximum life to the dry-cell of the lighting circuit. Further, the novelty of having a toy which lights up only when the toy is being pulled is instructive and of lasting fascination and pleasure from the standpoint of a child.

The present invention has another desirable advantage in that it may be manufactured and sold at a very low cost, a most important consideration in the commercial marketing of any child's toy.

The particular embodiments of the invention shown in the drawing are to be considered as illustrative only, it being understood that the same may be varied, within the scope of the appended claim, without departing from the spirit of the invention.

I claim:

A toy automobile comprising a hollow body, wheels attached to said body to support the same upon a surface, a headlight lamp for said automobile and a battery cell mounted inside of said hollow body, and means for closing a circuit between said lamp and cell, said means including a cord by which said toy may be pulled, a resilient switch member supporting said lamp in said body, said cord attached to said switch member and extending outwardly from said body through an opening therein whereby when the end of said cord is pulled said switch member will be flexed to close said circuit to light said headlight lamp.

ALLAN D. STARR.
